UNITED STATES PATENT OFFICE.

THOMAS O. PAYNE, OF VICKSBURG, MISSISSIPPI.

ASH-SIFTER.

SPECIFICATION forming part of Letters Patent No. 510,930, dated December 19, 1893.

Application filed January 13, 1893. Serial No. 458,254. (No model.)

To all whom it may concern:

Be it known that I, THOMAS O. PAYNE, a citizen of the United States, residing at Vicksburg, in the county of Warren and State of Mississippi, have invented certain new and useful Improvements in Ash-Sifters; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to improvements in ash sifters, and it has for its object the provision of a neat, simple, compact and novel ash sifter that can be used either in the yard or in the rooms of a house, thus obviating the necessity of carrying the ashes to the yard below in order to sift them, and then being compelled to carry the cinders back to the rooms. This device is cheap in construction and effective in use, as will readily be seen.

The invention further consists in the novel construction and arrangement of parts hereinafter described, illustrated in the accompanying drawings, and more particularly pointed out in the claims hereunto appended.

In the accompanying drawings: Figure 1 is a vertical longitudinal section view of the ash sifter, showing the interior construction, with the cinder receptacle in the rear end of the box, and also showing, the cinder receptacle as a separate box secured to the rear end of the main box, in dotted lines. Fig. 2 is a vertical cross sectional view of the ash sifter. Fig. 3 is a plan view of the ash-pan receiving and dumping frame, secured in the top above the sifter, with a pan secured thereon. Fig. 4 is a longitudinal section taken vertically through the device and showing the pan holding and dumping device.

Referring to the drawings by letters A is a box or casing, preferably rectangular, and is provided with a cover B hinged at its rear end, or on the side of the box, as may be found most desirable and convenient. This top or cover may be of any suitable shape, but I prefer that shown in the drawings, and the said cover is provided in its top or front end with a hinged trap or door b. In the front or

free end of this trap or door I provide a small opening b', for a purpose hereinafter referred to. This cover B is so nicely fitted to the top 55 of the box A as to be practically dust proof. Secured within the cover just over the ash sifter or separator is an eccentrically mounted frame C for holding and dumping a pan of ashes, and it consists of a platform of wire or other 60 suitable material, held directly over the separator by suitable supports C* secured in the ends of the cover, as shown. These supports are secured to the platform C to one side of a central line thereof, as shown in Fig. 3. The 65 platform C is held in a horizontal position by means of a catch or retaining pin c. On each side of the platform C are retaining wires c' c' c' for holding the pan or other vessel containing ashes to the platform. These wires 70 are of different lengths in order to permit the insertion of the pan and retaining the same therein when the platform is dumped, as hereinafter explained, the long wires being on the same side of the platform as the supports C*, C*, as shown.

On one side of the box A at the bottom thereof is a rectangular opening into which is fitted a drawer or pan N. This pan fits snugly in this opening and covers the forward 80 end of the bottom of the box, and receives and holds the sifted ashes when they are shaken from the separator in the upper part of the box. The sifted ashes may be removed from the sifter at any time by withdrawing the ash 85 drawer, as is apparent. This drawer may rest either upon the bottom of the box, or it may be slid upon ways or tracks secured in said box in any suitable manner; in the drawings I have shown it resting upon ways or tracks 90 x, as the pan will then always be in a horizontal position, thereby rendering a closer and better fit of the front edges of the drawer to the sides of the box, thereby preventing dust escaping from said drawer into the room 95 or other place where the sifting is going on. In the upper portion of this box A are tracks or ways d, d, secured to the sides of the box longitudinally thereof. Upon these tracks or ways d, d, is supported and reciprocated a rec sifter or separator D. This separator is of a width to permit it to travel back and forth upon the tracks d, d, and in length it is somewhat shorter than the length of the box A, so

that it may be reciprocated therein upon the tracks or ways d, d' , by means of a handle d' attached to one end of the sifter and extending out through the end of the box, as shown. 5 This separator is of sufficient depth to prevent the ashes when placed in it from falling over its sides, and the bottom of which dips and inclines toward the rear end of the box, thus making the rear part of the separator 10 deeper than the front part, so that when the separator is reciprocated the cinders, &c., will be shifted toward the rear of the separator. In the rear end of this separator D is an opening D^* through which the cinders and other 15 things too large to pass through the sieve fall, as is evident, into a receptacle for their reception. On the under side of this separator at the rear end thereof is a chute for throwing the ashes forward in the ash pan. In the 20 rear portion of the box A is a partial height partition which separates the ash and cinder compartments, as shown. Secured in this partition is an incline or chute W which extends forward over a portion of the ash pan and 25 under the rear portion of the separator, and serves to guide and conduct the cinders and other matter falling from the opening in the rear end of the separator down into the cinder drawer or receptacle S.

20 If it is desired to the rear end of the box A may be attached a box or receptacle X, which connects with the box A through an opening X^* . In the box A leading to this opening is a chute W, and flared on either side so as to bring the side edges in contact with the sides of the 30 box A as shown at w . This chute extends up into the box A a sufficient distance to prevent the cinders and other matter that fall through the opening D^* in the rear end of the separator 35 from going into the ash pan or drawer in the bottom of the box A, and yet not interfering with the action of the separator, as will be apparent. In the rear end of the cinder box or receptacle is an opening into which is fitted a sliding pan or drawer S, which may be supported on the bottom of the box or on ways or tracks similar to the ways for the drawer in the forward end of the box. The cinder receptacle may be provided with a hinged 40 opening, dust proof, so that access may be had to the interior thereof.

If desired the device may be mounted upon suitable feet or legs, and may be of any size required. 45 The operation of this device is as follows: When it is desired to sift ashes the trap b is raised and a pan of ashes is placed upon the platform in the cover, and is securely held thereto by the wires c', c^2 . The trap is 50 then closed and the pin c withdrawn. The

platform on account of the way in which it is mounted upon the supports C^* will tumble and throw the ashes from the pan onto the separator. The platform C is then returned to its normal position by handle c^* and the pin c inserted to hold it in its proper place. The separator is then reciprocated by means of the handle d' , and the ashes will fall through the holes in the separator into the ash pan, while the cinders that cannot pass through the holes will be shifted backward down the inclined bottom, out through the opening in the rear end of the separator, onto the chute and down into the cinder drawer or receptacle. If it is desired to insert a shovelful at a time, the trap is raised, shovel of ashes inserted, door or trap closed, and ashes thrown upon the separator, which is reciprocated. 70

Having described my invention, what I claim, and desire to secure by Letters Patent, 80 is—

1. In an ash sifter of the character described a horizontal longitudinally reciprocating separator, having a rearwardly extending incline bottom, opening in the rear end thereof and handle therefor, ways upon which said separator slides, in combination with an eccentrically mounted dumping platform mounted above said separator, and provided with retaining wires on each side thereof, handle for 90 said dumping platform, and pin for holding said platform in a horizontal position, as and for the purpose set forth.

2. In an ash sifter of the character described a horizontally reciprocating sliding separator, 95 an opening in the rear end thereof and an incline bottom, and an eccentrically mounted turning or dumping platform above said separator and independent thereof, and a handle and hold pin therefor, as and for the purpose 100 set forth.

3. In an ash sifter of the character described a turning or dumping platform eccentrically mounted in the top of the ash sifter, a handle c^* for turning the said platform into a horizontal position, and pin c for holding said platform elevated, as and for the purpose set forth. 105

4. In an ash sifter of the character described a tumbling or dumping platform eccentrically mounted in the top of said ash sifter, and retaining wires, c', c^2 , arranged for operation as set forth. 110

In testimony whereof I affix my signature in presence of two witnesses.

THOMAS O. PAYNE.
